BRUSH

Filed May 28, 1930

IRVIN F. DITTMAR.

Patterson Wright Patterson Attorney

UNITED STATES PATENT OFFICE

IRVIN F. DITTMAR, OF WILLIAMSPORT, PENNSYLVANIA, ASSIGNOR TO THE CROMAR CO., OF WILLIAMSPORT, PENNSYLVANIA, A CORPORATION OF PENNSYLVANIA

BRUSH

Application filed May 28, 1930. Serial No. 456,408.

This invention relates to certain new and useful improvements in brush construction and method of making the same and more particularly to the method of making a brush with a hollow center in order to produce a fountain brush especially adapted to be used in machines for coating strips of flooring, the object being to provide a method by means of which a brush with a hollow center can be made which will be very strong and durable, a ferrule being embedded within the bristles of the brush to receive the nozzle for supplying liquid thereto.

Another object of my invention is to provide a brush with a sectional back formed of two telescoping sections between which are arranged the bristles which are secured therein under pressure by cement in such a manner that all danger of the bristles working out is prevented.

Another object of my invention is to provide a brush with means for reinforcing the bristles to each side of the opening formed therein to receive the nozzle.

Other and further objects and advantages of the invention will be hereinafter set forth and the novel features thereof defined by the appended claims.

In the drawing,

Figure 1 is a plan view of a blank from which one of the sectional back members is formed;

Figure 2 is a perspective view of one of the sections of the back;

Figure 3 shows the first method of dipping the ends of the bristles into a cement in order to allow the bristles to absorb the cement;

Figure 4 is a section through a bunch of bristles with a cone inserted therein in order to form a hollow within the bristles;

Figure 5 is a vertical section through a form with the sectional backs in position therein and the bristles being placed therein;

Figure 6 shows the sectional backs pressed together so as to securely clamp the bristles in the back; and

Figure 7 is a perspective view of the back of the brush constructed in accordance with my improved method.

In constructing a brush in accordance with my invention, I employ a pair of back members A constructed identically alike of sheet metal, such as prime coke tin, each back section being formed of a blank B as shown in Figure 1 which is bent on the dotted lines B', B² and B³ into the shape as shown in Figure 2 which provides a box-like back section composed of double bottom portions A', A² and inwardly projecting reinforcing portions A³ and as these sections are formed of flexible metal, they are adapted to telescope one within the other by bending inwardly the end walls A⁴ of one back section so as to allow it to telescope within the other back section, the bottom section A² being notched as shown at A⁵ whereby an opening will be formed in the back of the complete brush when the two sections have been forced together and secured as shown in Figure 7 through which can pass a supply nozzle.

The method of forming a brush is as follows:

A pair of sectional backs are placed in a rectangular form C which is provided with pressing members D operated by screws D'. These sections are arranged within the form C in expanded position over a centering plug E mounted in the form and over which is placed a ferrule F which is provided with an annular flange F' cut away as shown at F² to prevent the same from rotating or moving therein. The ferrule is provided with a threaded portion F³ through which a threaded nipple is adapted to pass for moving the brush towards and away from the strip to be coated.

A bunch of bristles G of the desired size is selected and the string usually employed for tying the bundle is removed and a rubber band H is placed around the bristles and the bristles are then placed in a receptacle I containing a cement J formed of powdered magnesite and liquid chloride in order to allow the ends of the bristles to absorb the cement. The bunch of bristles are then removed and a cone K is inserted into the end of the bunch of bristles containing the cement as shown in Figure 4, the point of the cone extending up into the body of the bundle of

bristles beyond the line of cement into the uncemented end of the bristles.

- The cement from the receptacle I is then poured into the box-like sectional back which has been arranged within the form C and the bunch of bristles with the cone K therein is inserted into the box-like member, the cone extending over the ferrule so as to protect the same and to allow a hollow place to be formed within the bundle of the bristles.
- 5 The bundle of bristles is then worked down into the back, either by a knife or any other suitable instrument and the bristles are distributed uniformly in the back. The rubber band having been removed from the bundle of bristles, the cone K is drawn upwardly out of the bunch of bristles and the clamp screws D' operating the pressing members D are then turned so as to force the two sections 10 of the back together until the indicating marks, which are arranged on the form for indicating the distance the members D should be moved inwardly, have been reached, which forces the two sections together, causing one section to telescope within the other, the reinforcing members moving inwardly towards each other so as to reinforce the bristles around the opening thus formed.
- The form is then turned upside down and 15 vibrated so as to shake off the surplus cement which has been squeezed out and the form is then placed upside down in a heated room or over a steam radiator and after remaining in a warm place for twenty-four 20 hours, a suitable instrument is forced down through the brush and the plug E is driven out through the bottom of the form and then the pressure screws are unscrewed so as to release the brush thus formed, which is removed from the form and the outside of the brush is thoroughly cleaned with a wire brush and the bristles combed with a brush-maker's comb and all projecting bristles are 25 cut off.
- 45 The joints of the two sectional backs which are held in this position by the cement are then cleaned and soldered as shown at L in Figure 7 and the brush thus formed is complete.
- 50 By this method a brush can be formed with a hollow portion to receive a supply nozzle located centrally or at any desired position and in the embodiment of my invention as herein shown the ferrule embedded within 55 the brush to receive the liquid supply nozzle is arranged off-center so that when the brush is used in connection with a machine for coating flooring, the supply of liquid will be delivered to the upper portion of the brush.
- 60 From the foregoing description it will be seen that I have provided a novel method of making a fountain brush with an opening formed by placing the bristles around a ferrule to form a receiving opening for the nozzle used for supplying liquid thereto where-

65 by I produce a brush which has many advantages over brushes of this kind now in use.

70 By using a heat-proof cement, such as a cement formed of powdered magnesite and liquid chloride, I am able to use my brush with a heated coating liquid which can be heated to a high temperature without any disintegration taking place.

75 What I claim is:

1. A brush formed of a pair of box-like double bottom telescoping back sections secured around one end of a bunch of bristles, a ferrule arranged within said back and extending into said bristles, said back being provided with oppositely disposed inwardly projecting reinforcing members extending into said bristles to each side of said ferrule.

80 2. A brush composed of a back formed of two box-like sections having double bottom portions, said sections being adapted to telescope one within the other, bristles disposed in said back and secured therein by cement, said box-like sections being secured together around said bristles.

85 3. As a new article of manufacture, a brush having a back formed of duplicate box-like sections, the bottom of each section being formed double, one section being adapted to telescope within the other section, bristles secured within said back and a ferrule embedded within said bristles adapted to receive a supply nozzle.

90 4. As a new article of manufacture, a brush formed of a pair of rectangular box-like sections, each section having a double bottom, one bottom of each section being provided with a notch, said sections adapted to telescope within one another, a ferrule arranged within the notches of said sections, bristles disposed in said sections and members extending inwardly from each section to each side of said ferrule.

95 In testimony whereof I hereunto affix my signature.

100 IRVIN F. DITTMAR.
